G. R. JOUGHINS

RAILWAY BOX FREIGHT CAR

Filed Jan. 8, 1927

FIG. 2

FIG. 3

FIG. 1

FIG. 4

George R. Joughins.
Inventor.

UNITED STATES PATENT OFFICE.

GEORGE R. JOUGHINS, OF ELIZABETH, NEW JERSEY.

RAILWAY BOX FREIGHT CAR.

Application filed January 8, 1927. Serial No. 159,962.

My invention embraces the construction of steel railway box car bodies having steel floors and self-supporting sides, all preferably of pressed forms of corrugated steel which entirely eliminates the usual side sills, and the usual side framework consisting of steel struts and braces and the use of lumber; with the object of simplifying the construction of said cars and of materially reducing the number of parts and the amount of labor involved in their manufacture.

In the accompanying drawing Figure 1 is an outline side elevation of the box car. Figure 2, on a larger scale, a half section transverse elevation at A—A, and a half section through the side at B—B in Figure 1. Figure 3, a sectional plan of the preferred construction of the corner joining the sides and ends, and Figure 4, a section of a fragment of the flooring.

The side sheets, 1, are designed to be of pressed steel, girder shaped, moulded from sheets of the largest commercial sizes which may be convenient, riveted together and of sufficient thickness to be self supporting without the usual side sills, and preferably of corrugated form. The edges of these side sheets may be strengthened by flanges, 2, at the top edge and, 3, at the bottom, and may be further re-enforced by strips, 4, at the top and, 5, at the bottom to increase the strength of the girder form of side, particularly under the doorway. The words, self-supporting, applied above to the side sheets, mean to include the proportion of the lading usually upheld by the side sills.

The floor, 6, is also composed of sheet metal

plates, preferably of corrugated form, as indicated in Figure 4, suitably flanged to enable them to be riveted to each other and to the side and end sheets. The corrugations may be filled with cement if necessary to make a smooth floor.

The doorways, 7, are flanged, at 8, all around, preferably inwardly as shown. Transverse braces, 9, are applied from doorway to doorway at the top, attached firmly to the flanges, 8, to prevent excessive torsion of the car body at its center. 10 are the center sills, 11, the intermediate sills and, 12, the carlines.

I claim:

1. A railway box freight car having its sides constructed of self-supporting metal sheets longitudinally disposed substantially as described.

2. A railway box freight car having its sides constructed of self-supporting pressed steel corrugated sheets substantially as described.

3. A railway box freight car having its sides constructed of self-supporting metal sheets which form a continuous girder from end to end, substantially as described.

4. A railway box freight car having its flooring constructed of corrugated sheets of metal transversely disposed, substantially as described.

5. A railway box freight car having its sides constructed of self-supporting metal sheets and having flanged doorways cut therein substantially as described.

GEORGE R. JOUGHINS.
